[57] **CLAIM**

The ornamental design for a reflective pet toy, as shown and described.

DESCRIPTION

FIG. 1 is a front elevational view of a reflective pet toy showing my new design;

FIG. 2 is a side elevational view thereof, the opposite side elevational view being identical;

FIG. 3 is a rear elevational view thereof;

FIG. 4 is a top plan view thereof;

FIG. 5 is a bottom plan view thereof; and,

FIG. 6 is a perspective view thereof, the broken lines are for purposes of illustration only and form no part of the claimed design.

FIG. 1

FIG. 2

FIG. 3

FIG. 4

FIG. 5

FIG. 6
